UNITED STATES PATENT OFFICE.

DANIEL I. REITER, OF NEW YORK, N. Y.

KEY HOLDER.

Application filed May 31, 1923. Serial No. 642,651.

To all whom it may concern:

Be it known that I, DANIEL I. REITER, a citizen of the United States, and a resident of the city of New York, borough of Manhattan, in the county and State of New York, have invented a new and Improved Key Holder, of which the following is a full, clear, and exact description.

This invention relates to a key holder, and 10 has for an object the provision of a construction or plate to which a plurality of key holding elements are attached.

Another object concerns the provision of 15 a plate construction whereby the key holding elements after once being attached to the plate cannot be removed after the plate has been completely formed into its ultimate shape.

A further object concerns the provision of 20 a plate construction in which the assembly of the key holding elements thereon and the formation of the plate into its ultimate condition involves a very simple process.

The invention is illustrated in the drawings, of which—

Figure 1 is an elevation of the plate to which the key holding elements are attached;

Fig. 2 is a section taken through said plate, as illustrated in Fig. 3;

Fig. 3 is a partial elevation of the plate in 30 the course of its formation;

Fig. 4 is a section through the plate when completely formed; and

Fig. 5 is a partial elevation of said plate 35 when completely formed.

The form of the invention shown in the drawings is a preferred form, although it is understood that modifications in the construction and arrangement of the parts and 40 in the character of the materials used may be adopted without departing from the spirit of the invention.

This invention is a development of the idea set forth in my co-pending application, 45 Serial No. 580,747, filed August 9, 1922, entitled "Holder for keys". That invention, briefly, comprises the provision of a plate to be attached to a flexible casing or backing, said plate having one or more slots formed therein, preferably transverse to the upper edge of the plate, and adjacent the upper edge of the plate provided with offset enlarged slot portions connected to the main slots, which are considerably smaller than 55 the enlarged portions, by lateral passages. The upper portion of the plate is rolled back

so that when in actual use the enlarged portions of the slots lay flat against the backing. Key holding elements having enlarged head portions and relatively narrow stem portions 60 are slidably mounted in said slots, the head portions being introduced through the enlarged portions, this introduction permitting the stems to be slipped through the lateral passages into the main slot. The rolling of the plate thereafter so obstructs the enlarged offset portions of the slots as to prevent the heads of the keyholder from being moved into the enlarged portions whereby they might be removed. However, this 70 obstruction of the enlarged portions of the slots only occurs in this former invention when the flexible backing is attached to the plate.

This improvement of that invention contemplates the construction and formation of the plate itself without regard to the flexible backing, so that after the key holding elements have been inserted in the slots and the plate has been formed, the key holding 75 elements cannot be removed, whether the plate is fastened to the backing or not.

To this end, as shown in the drawings, which illustrate a preferred form of the invention, I provide the plate 1 with one or 80 more main slots 2, relatively long and narrow and extending preferably transversely of the upper edge 3 of the plate. These slots may extend all the way through to the edge of the plate or be terminated adjacent 85 said edge. At the upper end of each slot 2, and offset therefrom, is an enlarged portion 4 connected to the slots 2 by lateral passages 5.

In each slot 2 there is adapted to be slidably mounted a key holding element 6 having a stem 7 and an enlarged head 8 thereon. The stem 7 is of a size small enough to permit its sliding in the slot 2 and in a lateral passage 5, but the head 8 is too large to pass 90 through said slot and passage, but it is not too large to be introduced through the enlarged portion 4; therefore these key holding elements can be introduced into the slots 2 by first passing the heads 8 through the 95 enlarged portions 4 and moving the stems 7 through the lateral passages 5 into the main slots 2.

After this occurs, and the various key elements are mounted in their respective slots, 100 the plate is rolled, as shown in Fig. 2, along its upper portion so that the enlarged por-

tions 4 of the slots are presented toward the rear of the plate. Previous to this the plate has been bent or offset, preferably adjacent but below the lower end of the slot 2, to provide a shoulder 9. This offset is provided in the direction of the front of the plate, whereas the upper end of the front is rolled to the rear and, as shown in Fig. 2, has been bent so as to lie somewhat adjacent the shoulder 9. As observable from a consideration of Fig. 3, the off setting of the plate has not only provided the shoulder 9 disposed horizontally but has provided a vertical wall 10 in front of the shoulder, which, as seen in Fig. 5, when the edge 3 has been advanced downwardly to lie against the shoulder 9 will partly obstruct the lateral passages 5 and, therefore, prevent the stems of the key holding elements 7 from being moved out of the slots 2 in the enlarged portion 4, whereby the heads 8 might be removed from the plate through these enlarged portions. In this manner, therefore, I have been able to roll the upper end of the plate as hitherto, but in addition I have provided a simple means whereby the lateral passages can be obstructed while at the same time the rear surface of the plate is smooth and uninterrupted, so that as shown in dotted lines in Fig. 4, the flexible backing or casing 11 will lie flat thereagainst and can be connected thereto in any suitable manner.

In the manufacture, therefore, of this device, the slots are formed and the plate is rolled into the position shown in Fig. 3; then the key holding elements are inserted with their heads through the enlarged portions; after which the stems are slipped into the main slots in the manner described and the key holding elements are advanced to the position shown in Fig. 4, where they lie along the front of the plate. The lower portion of the plate is then further operated upon to advance the edge 3 downwardly so that it lies flat against the shoulder 9, and in this position the wall 10 obstructs the passage 5 partly if not wholly, so that the key holding elements cannot be removed from the plate, therefore, until this rolled portion has been partly unrolled or removed from the vicinity of the wall.

What I claim is:—

1. A key holder construction, which includes a plate having a slot disposed transversely to one edge, said plate having an enlarged slot portion adjacent the main slot and connected thereto by a lateral passage, that portion of the plate adjacent said edge and said enlarged slot portion being rolled or bent on itself so that in the ultimate position of the plate the enlarged

slot and the lateral passage lie adjacent the body of the plate, whereby they are to some extent obstructed.

2. A key holder construction, which includes a plate having a slot disposed transversely to one edge, said plate having an enlarged slot portion adjacent the main slot and connected thereto by a lateral passage, that portion of the plate adjacent said edge and said enlarged slot portion being rolled or bent on itself so that in the ultimate position of the plate the enlarged slot and the lateral passage lie adjacent the body of the plate, whereby they are to some extent obstructed, a key holding element adapted to be supported in said main slot, and an enlarged head portion on said key holding element, the obstruction of the lateral passage in said enlarged slot portion prohibiting the removal of the head of the key holding element from the main slot.

3. A key holder construction, which includes a plate, the upper portion of which is rolled back on itself, a shoulder formed in said plate below but adjacent the rolled portion, the edge of the plate which has been bent back on itself adapted to engage and lie against said shoulder.

4. A key holder construction, which includes a plate having a slot disposed transversely to one edge, said plate having an offset enlarged slotted portion adjacent the end of the slot lying near said edge, said plate having a lateral passage connecting the main slot with the enlarged portion, a shoulder formed in the plate adjacent but below the other end of said slot, a vertical wall adjacent said shoulder, the upper end of the plate being rolled back on itself to project downwardly and lie against said shoulder, the lateral passage and said enlarged portion of the slot being at least partly obstructed by the wall adjacent said shoulder, a key holder element having a stem adapted to slide in the main slot, and an enlarged head portion on said element, the removal of the head portion from the plate being prohibited by the obstruction of the lateral passage and the enlarged slot portion through which the head must be removed.

5. A key holder construction, which includes a plate having a slot adjacent one edge, the upper portion adjacent said edge being rolled back on itself, a shoulder formed in the plate below but adjacent the edge of the rolled portion, the edge of the plate which is bent back on itself adapted to engage and lie against said shoulder, whereby the end of the slot is obstructed.

DANIEL I. REITER.
